UNITED STATES PATENT OFFICE.

KARL BAUMANN, OF URMSTON, ENGLAND, ASSIGNOR TO THE BRITISH WESTINGHOUSE ELECTRIC & MANUFACTURING COMPANY, LIMITED, OF LONDON, ENGLAND.

FEED-WATER HEATER.

1,276,860.

Specification of Letters Patent. Patented Aug. 27, 1918.

Application filed May 1, 1916. Serial No. 94,792.

To all whom it may concern:

Be it known that I, KARL BAUMANN, a citizen of the Confederation of Switzerland, and a resident of Urmston, in the county of Lancaster, England, have invented a new and useful Improvement in Feed-Water Heaters, of which the following is a specification.

This invention relates to feed water heaters of the jet or contact type, that is of the type in which heat is communicated to the feed water by direct contact with the heating steam. More particularly the invention has for its object to provide an improved or "multi-stage" feed water heater of the above type, which is adapted to utilize low pressure heating steam at different pressures obtained for example from two or more points in a low pressure stage of a steam 15 turbine or from a low pressure stage and from the packing glands of a turbine.

The improved jet type feed water heater of this invention comprises a plurality of heaters connected by semi-barometric legs, the water from the first heater discharging at an increased pressure into a second heater, and from there being discharged to the hot well and recorder tank by a pump hereinafter referred to as the "lift" pump. 20 Where more than two heaters are used the water from the second heater passes at a still further increased pressure to the next succeeding heater and so on until it reaches the final heater from which it is removed by the lift pump. Alternatively the water from the final heater of the series may be discharged through a barometric leg into a seal well and removed therefrom by a lift 25 pump.

Several ways in which the invention may be carried out in practice are illustrated diagrammatically by way of example in the accompanying drawings, in which Figure 1 represents a two-stage heater constructed in accordance with the invention, and Figs. 2 and 3 are fragmentary views illustrating modifications in the arrangement shown in Fig. 1. Fig. 4 shows a three-stage heater of a somewhat different construction from 30 that represented in Figs. 1 to 3.

Referring now to Fig. 1, the first heater is indicated at 5 and the second heater at 6, the two heaters being connected by a short or semi-barometric leg 7 through 35 which the feed water passes from the first

to the second heater. Heating steam from the source of lower pressure is admitted through the inlet 8 to the heater 5 and from the source of higher pressure through the inlet 9 to the heater 6. The condenser discharge pump is shown at 10 and supplies water to the heater 5 through the pipe 11. The heated water is withdrawn from the second heater 6 by a lift pump 12 which delivers through the pipe 13 to the hot well, recorder tanks, or elsewhere as may be required. A float operated valve 14 is preferably provided in the water supply pipe 11 for the purpose of controlling the supply of water to the heater 5. The object 40 and operation of such a float operated valve is fully set forth in my concurrent application No. 7335, filed 15th May 1915.

The steam supplied to the heaters through the inlets 8 and 9 usually contains air 45 which, together with any other air or incondensable gases finding their way into the heater, must be extracted therefrom and, for this purpose, as shown in Fig. 1, the first heater 5 is connected at 15 by a pipe or passage with the main condenser. The second heater 6 may also be similarly connected with the main condenser but I prefer to connect the steam space of the second heater 6 with the steam space of the first 50 heater 5 through a pipe 16. An automatic relief valve 18 is inserted in the connecting pipe 16, which valve is adjusted to maintain the pressure in the second heater 6 above that in the first heater 5 by the desired amount and, at the same time, prevent undue leakage of steam from the second heater 6 into the first heater 5 while permitting any excess of steam in the second heater 6 to pass to the first heater 5.

The lower end of the semi-barometric leg 7 within the second heater is provided with an upward extension or bend 19 through which the water flows in an upward direction into the second heater 6. Said upward extension or bend 19 acts to prevent steam or air from the second heater 6 escaping into the first heater 5 through the barometric leg 7. The length of the barometric leg 7 between the two heaters must be such as to form an effective seal between them, having in mind the difference in pressure which should normally exist between the heaters 5 and 6.

The employment of the relief valve 18 in 110

the connection 16 between the two heaters enables the valve 14 in the water supply pipe to the heater to be controlled by a single float 20. This float may be either in the first or the second heater, or a float chamber connected therewith, as may be found most convenient although it is preferable to have the float in the second heater as shown in Fig. 1.

10 The automatic relief valve 18 may be actuated by a float in one or the other of the heaters or in a float chamber connected therewith. If the float controlling the valve 14 in the water supply pipe 11 is in the first heater 5 then the float controlling the relief valve 18 must be in the second heater and must act to close the relief valve when the water level in the second heater rises. In Fig. 2 the relief valve 18 is shown as being controlled by a float 21 located in a float chamber communicating with the first heater 5 in such a manner that the relief valve 18 will be opened when the water level in the first heater 5 rises. With this arrangement the valve 14 in the water supply pipe 11 of the heater is controlled by a float in the second heater 6 as illustrated in Fig. 1.

In some cases, instead of depending solely upon the automatic relief valve 18 for permitting the discharge of air from the second heater 6 into the first heater 5, or into the condenser, I provide in addition a by-pass 22 around the valve 18 in the pipe 16 connecting the two heaters. A valve 23 is preferably provided for adjusting the size of said by-pass 22.

In addition to or in place of the relief valve 18 in the connection 16 between the two heaters I sometimes provide a siphon tube 24 containing sealing water, as illustrated in Fig. 3. In the event of the pressure in the second heater 6 rising above a predetermined degree the sealing water in the siphon tube 24 will be blown out and the excess steam in the second stage of the heater will escape therethrough to the first heater. Valves 25, 26 may be provided in the siphon tube 24 for enabling the same to be refilled with water while the heater is in operation. Where the relief valve is replaced by the siphon tube 24 an additional by-pass in the form of a second pipe 27 interconnecting the two heaters is provided, said pipe preferably having a regulating valve 23 as described with reference to Fig. 1.

Fig. 4 shows an alternative construction for a heater adapted to utilize steam from three sources at different pressures. The first heater is indicated at 5, the second at 6, and a third heater at 28. The steam inlets to said heaters are shown respectively at 8, 9 and 29. The semi-barometric leg connecting heaters 5 and 6 is indicated at

7 and a similar leg, connecting heaters 6 and 28, at 30. The water passing through the barometric leg 31 from the heater 28 may have an atmospheric discharge or be removed directly by a lift pump, as shown 70 in Fig. 1.

Although heaters having only two or three stages have been herein described and illustrated it is to be understood that heaters may be constructed having more 75 than three stages without departing from the scope of the invention.

Having now particularly described and ascertained the nature of my said invention and in what manner the same is to be used, I declare that what I claim is:—

1. A multi-stage feed water heater of the jet or contact type adapted to utilize low pressure steam comprising a plurality of heater chambers, a steam connection to each chamber, semi-barometric legs connecting said chambers in such manner that the water passes through the same in series, means for removing water from the last chamber of the series, and automatically controlled means for venting one chamber to the chamber of next lower pressure.

2. A multi-stage feed water heater adapted to utilize low pressure steam at different pressures, comprising a plurality of 25 heater stages through which water to be heated passes in series, means for delivering steam to each stage, means for removing water from the final stage, and means for automatically venting the final stage to 100 the preceding stage.

3. A multi-stage feed water heater adapted to utilize low pressure steam at different pressures, comprising a plurality of 105 heater stages through which the water to be heated passes in series, means for delivering steam to each stage, a lift pump for removing water from the final stage, and valved means constructed to automatically vent the final stage into the preceding 110 stage upon a predetermined rise in pressure in the final stage.

4. A multi-stage feed water heater adapted to utilize steam at different pressures, comprising two stages through which the 115 water is adapted to pass in series, a semi-barometric leg between said stages and provided with an upwardly turned extension at its delivery end through which water is adapted to pass in entering the 120 second stage, and a valved passage connecting the steam spaces of said stages.

5. A multi-stage feed water heater comprising at least two stages through which water to be heated passes in series and adapted to receive heating fluid at a different pressure, a pipe or passage connecting said stages, and an automatic relief valve located within said pipe or passage.

6. A multi-stage feed water heater com-

prising at least two stages through which water to be heated passes in series and adapted to receive heating fluid at a different pressure, a pipe or passage connecting said stages, an automatic relief valve located within said pipe or passage, and a bypass passage around said relief valve.

In testimony whereof I have hereunto subscribed my name this third day of April, 1916.

KARL BAUMANN.
